[57] **CLAIM**

The ornamental design for the transport container with flap doors, as shown and described.

DESCRIPTION

FIG. 1 is a perspective view from above one corner showing the front wall and one side wall of my new design for a transport container with flap doors;

FIG. 2 is a perspective view from above the corner which is diagonally opposite the corner designated in the FIG. 1 description showing the back wall and the other side wall thereof;

FIG. 3 is a top plan view looking down into the interior of the container showing the top edges of all four walls and the interior surface of the bottom of the container; and,

FIG. 4 is a bottom plan view showing the exterior of the bottom of the container.
